(57) **CLAIM**

The ornamental design for a transaction card holder, as shown and described.

DESCRIPTION

FIG. 1 is a front perspective view of a transaction card holder according to an embodiment of the invention;

FIG. 2 is a front elevation view of the transaction card holder of FIG. 1;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the drawings depict portions of the article and form no part of the claimed design.
